(57) **CLAIM**

The ornamental design for a top cover for a material handling vehicle, as shown and described.

DESCRIPTION

In a preferred embodiment, the nature of this product is as a top cover useful in connection with a material handling vehicle.

FIG. 1 is a top, left, front perspective view of a top cover for a material handling vehicle embodying our new design;

FIG. 2 is a front elevational view thereof;

FIG. 3 is a top plan view thereof;

FIG. 4 is a left side elevational view thereof; and,

FIG. 5 is a right side elevational view thereof.

The broken line representations of portions of the top cover in FIGS. 1-5, are for the purpose of illustration only, and form no part of the claimed design.
